(57) **CLAIM**

The ornamental design for a nonwoven fabric, as shown and described.

DESCRIPTION

FIG. 1 is an isometric view of a nonwoven fabric showing our new design;

FIG. 2 is a top plan view thereof;

FIG. 3 is an isometric rear view thereof;

FIG. 4 is a rear plan view thereof;

FIG. 5 is an isometric view of a second embodiment of our new design;

FIG. 6 is a top plan view thereof;

FIG. 7 is an isometric rear view thereof;

FIG. 8 is a rear plan view thereof;

FIG. 9 is an isometric view of a third embodiment of our new design;

FIG. 10 is a top plan view thereof;

FIG. 11 is an isometric rear view thereof; and,

FIG. 12 is a rear plan view thereof.

The pattern of the design repeats uniformly throughout the surface of the nonwoven fabric. The broken lines forming an edge surrounding the design represent the boundaries of the nonwoven fabric and form no part thereof.
